(57) **CLAIM**

The ornamental design for an adapter for ammunition magazines, as shown and described.

DESCRIPTION

FIG. 1 is a front elevation view of a first embodiment of the adapter for ammunition magazines.

FIG. 2 is a rear elevation view of the first embodiment of the adapter for ammunition magazines.

FIG. 3 is a left side elevation view of the first embodiment of the adapter for ammunition magazines.

FIG. 4 is a right side elevation view of the first embodiment of the adapter for ammunition magazines.

FIG. 5 is a top view of the first embodiment of the adapter for ammunition magazines.

FIG. 6 is a bottom view of the first embodiment of the adapter for ammunition magazines.

FIG. 7 is a left isometric view of the first embodiment of the adapter for ammunition magazines.

FIG. 8 is a right isometric view of the first embodiment of the adapter for ammunition magazines.

FIG. 9 is a front elevation view of a second embodiment of the adapter for ammunition magazines.

FIG. 10 is a rear elevation view of the second embodiment of the adapter for ammunition magazines.

FIG. 11 is a left side elevation view of the second embodiment of the adapter for ammunition magazines.

FIG. 12 is a right side elevation view of the second embodiment of the adapter for ammunition magazines.

FIG. 13 is a top view of the second embodiment of the adapter for ammunition magazines.

FIG. 14 is a bottom view of the second embodiment of the adapter for ammunition magazines.

FIG. 15 is a left isometric view of the second embodiment of the adapter for ammunition magazines.

FIG. 16 is a right isometric view of the second embodiment of the adapter for ammunition magazines.

FIG. 17 is a front elevation view of a third embodiment of the adapter for ammunition magazines.

FIG. 18 is a rear elevation view of the third embodiment of the adapter for ammunition magazines.

FIG. 19 is a left side elevation view of the third embodiment of the adapter for ammunition magazines.

FIG. 20 is a right side elevation view of the third embodiment of the adapter for ammunition magazines.

FIG. 21 is a top view of the fourth embodiment of the adapter for ammunition magazines.

FIG. 22 is a bottom view of the fourth embodiment of the adapter for ammunition magazines.

FIG. 23 is a left isometric view of the fourth embodiment of the adapter for ammunition magazines; and,

(Continued)

FIG. 24 is a right isometric view of the third embodiment of the adapter for ammunition magazines. The broken lines in the drawings depict unclaimed portions of the adapter only and form no part of the claimed design.
